US00D713691S

(12) **United States Design Patent**
Sabounjian

(10) **Patent No.:** **US D713,691 S**
(45) **Date of Patent:** **** Sep. 23, 2014**

(54) **COFFEE POD HOLDER**

(75) Inventor: **Azad Sabounjian**, Irvine, CA (US)
(73) Assignee: **Pro-Mart Industries, Inc.**, Irvine, CA (US)

(**) Term: **14 Years**

(21) Appl. No.: **29/431,045**

(22) Filed: **Aug. 31, 2012**

(51) **LOC (10) Cl.** **07-06**

(52) **U.S. Cl.**

(57) **CLAIM**

The ornamental design for a coffee pod holder, as shown and described.

DESCRIPTION

FIG. 1 is a top, front, right perspective view of a first embodiment of a coffee pod holder showing my new design;

FIG. 2 is a top, front, right perspective view shown partially open thereof;

FIG. 3 is a front elevational view of FIG. 1;

FIG. 4 is a right side elevational view thereof;

FIG. 5 is a rear elevational view thereof;

FIG. 6 is a left side elevational view thereof;

FIG. 7 is a top plan view thereof; and

FIG. 8 is a bottom plan view thereof.

FIG. 9 is a top, front, right perspective view of a second embodiment of a coffee pod holder showing my new design;

FIG. 10 is a top, front, right perspective view shown partially open thereof;

FIG. 11 is a front elevational view of FIG. 1;

FIG. 12 is a right side elevational view thereof;

FIG. 13 is a rear elevational view thereof;

FIG. 14 is a left side elevational view thereof;

FIG. 15 is a top plan view thereof; and,

FIG. 16 is a bottom plan view thereof.
